UNITED STATES PATENT OFFICE.

JAMES F. ATWOOD, OF MALDEN, MASSACHUSETTS.

GARMENT-SUPPORTING CLASP.

SPECIFICATION forming part of Letters Patent No. 534,679, dated February 26, 1895.

Application filed January 8, 1895. Serial No. 534,232. (No model.)

To all whom it may concern:

Be it known that I, JAMES F. ATWOOD, a citizen of the United States, residing at Malden, in the county of Middlesex and State of Massachusetts, have invented a new and useful Improvement in Garment-Supporting Clasps, of which the following is a specification.

This invention relates to garment-supporting clasps of the general style illustrated in the Letters Patent of the United States granted to me January 5, 1886, and numbered 333,495, to which reference is made; and the improvement consists in the below described construction, whereby the device is simplified and improved in action, as illustrated in the accompanying drawings, in which—

Figure 1 is a front elevation of my improved clasp in the position assumed when a garment is clamped. Fig. 2 is a side view of the same. Fig. 3 is a side view in the position assumed when the clasp is about to fly open. Fig. 4 is a vertical section showing the clasp open. Fig. 5 is a view of the back plate detached.

Similar letters of reference indicate corresponding parts.

A is the back plate, consisting of a flat piece of metal turned up into a lip A' at its lower end, and slotted vertically at a' at its upper end as shown, the two outer of the three sections thus formed being turned over at a'', and the central section a' constituting a spring, all as in the Letters Patent above referred to.

The folds a'' provide for a pin B, by means of which the cam-link E is hinged to the back plate, and said cam-link is pivotally secured to a front plate D between inwardly turned lips or folds D', by means of a loop F which extends through said folds D' and the front portion of said cam-link as shown. To the upper portion F' of this loop the webbing or tab is to be connected, whereby the clasp is suspended. The sides F'' are bent rearward or curved as shown.

Extending outward from the back plate A, beyond the folds a'' are edges or ledges H, and extending inward or rearward from the upper end of the front plate D, between the folds D', is a lip or spring K.

When the clasp is closed, the lower end of the front plate D is forced down into the hollow formed by the lip A', with the spring a'

bearing against the rear side of the cam-link, as in the said Letters Patent. It will be noticed however, that the loop F is connected at the point where the cam-link is pivoted to the front plate, instead of at the point where it pivoted to the rear plate, as in the said Letters Patent.

When the clasp is in use, the portion F' of the loop is about over the back plate, the portions F'' being bent rearward and touching lightly or nearly touching the edges H.

When the clasp is to be opened, the loop is forced back, the edges or wings H H acting as fulcrums for the side portions F'' of the loop, which act as levers. As the loop is forced back, it assumes the position shown in Fig. 3, and then the lower end of the front plate D flies up from the lip A' into the position shown in Fig. 4, the springs a' and K assisting. Thus no tab, such as shown at C' in said patent is needed.

Having thus fully described my invention, what I claim, and desire to secure by Letters Patent, is—

1. In a garment-supporting clasp, the combination of the back plate A formed with the lip A' at its lower end and provided with the outward extensions H on its upper edge, the cam-link B pivotally connected with the back plate, the front plate D pivotally connected at its upper edge with the cam link, and the loop F F' F'' extending from the point of connection between the cam-link and front plate and adapted to have its side arms act as levers upon the said extensions in opening the clasp, substantially as set forth.

2. In a garment-supporting clasp, the combination of the back plate A formed into the lip A' at its lower edge and provided with the outward extensions H on its upper edge and the spring a', the front plate D provided with the spring or lip K, the cam-link E connecting said front and back plates and pivoted thereto, and the loop F F' F'' secured to the clasp at the hinged connection of the cam-link with the front plate and bent rearward as shown, substantially as described.

JAMES F. ATWOOD.
